UNITED STATES PATENT OFFICE.

ALFRED CARL FRIEDRICH RATHKE, OF LEIPZIG, GERMANY, ASSIGNOR TO KÜHL-TRANSIT-VERKEHRS-AKTIENGESELLSCHAFT, OF LEIPZIG, GERMANY.

HEAT-TIGHT AND AIR-TIGHT CLOSING DEVICE FOR DOORS.

Application filed July 12, 1926, Serial No. 121,995, and in Germany July 29, 1925.

Doors for refrigerator cars, cold stores or other rooms to be closed heat-tightly or air-tightly must fit closely along their entire contours, in order to fulfill their purpose, 5 so that any heat- or air-exchange is prevented. It is not at all sufficient to press, for instance double wing doors, at the outer end, as the pressing on the line of closing can compensate for the progressing compression of the packing material of the 10 door but not at the sides where the hinges are, as at these no automatic adjusting is possible and the door gets very soon leaky at the hinged side and at a portion along 15 the upper and lower door sills.

Door-closing devices have become known which account for the preceding by making the hinges movable in oblong holes perpendicularly to the plane of the door and by 20 pressing the hinge sides on by means of special pressing elements as bolts, cam shafts or eccentrics which are more or less connected with the main closing device so as to obtain along the entire contour of the 25 door a uniformly increased pressing depth in accordance with the gradual compression of the packing material.

According to the invention no such special latching elements are required as, in 30 opposition to the closing devices of known type the door is made air-tight and heat-tight by enlarging the contact surface of the door wing in the direction towards the hinge sides, this surface enlarging being controlled accordingly.

The improved closing device utilizes, with this object in view, besides a latching bar of suitable construction and besides the elements upon which this bar acts, only those 40 portions of the door which must normally exist, i. e. the door wings and their hinges. The door is pressed on along its contour by means of the latching bar, for the operation of which one single manipulation is sufficient and which causes a displacement 45 of the door wings in lateral directions so that the necessary packing and the automatic re-adjusting of the pressing depth is obtained in the simplest manner,

50 An embodiment of the invention in its application to a double-wing hinge-door for a refrigerator car is shown, by way of example, in the accompanying drawing, in which:—

55 Figs. 1 to 5 show the unlatched door in

Fig. 1 in front elevation and in Fig. 2 in plan view.

Fig. 3 shows the position of the hinge.

Fig. 4 is a section through the upper door sill and

Fig. 5 is a section through the lower door sill.

Figs. 6 to 10 show the door in latched state in Fig. 6 in front elevation and in Fig. 7 in plan view.

Fig. 8 shows the position of the hinge.

Fig. 9 is a section through the upper door sill and

Fig. 10 is a section through the lower door sill.

The closing device consists of a latching rod 1 having at the top end two latching rollers 2 fixed by a bolt, a latching wedge 3 near the lower end and two wedges 4 on the central parts. A double wedge 5 on, 75 the upper door frame is designed to cooperate with the rollers 3. On the lower door frame a roller 6 is fixed (Figs. 5 and 10) which is designed to guide the lower wedge 3. On each door wing a pushing roller 7 is fixed by a bolt and bow (Figs. 1 and 6) and designed to transmit upon the door wings the forces exerted by the pushing wedges 4. In order to avoid, as much as possible, any friction from sliding the pressures exerted by the latching rod 1 are transmitted by rollers instead of by sliding surfaces. The latching rod 1 can be moved up and down by means of the hand lever 8 and the lever 9. To guide the latching rod 1 as much as possible without friction 85 it has slots 10 (Figs. 4 and 9) with which engage guides 11. These guides 11 are pivotally mounted in guide blocks 12 and they are designed to transmit upon the door wing on which they are fixed the pressing on pressures which are produced at the middle.

The hinges 13 on the door wings are of oval cross section (Fig. 3) the axes of the ovals of all the door hinges standing at the same 100 acute angle α with regard to the plane of the door so that the open side of the angle is turned towards the latching rod 1. (Figs. 3 and 8).

To close the door the rod 1 is pressed 105 downward by means of the handle 8 and lever 9 whereby the pushing wedges 4 are made to pass along the pushing rollers 7, the rollers 2 along the double wedge pieces 5 and the wedge surface 3 along the rollers 110

6. At this occasion two movements take place: the wedges 4 push first the door wings through the intermediary of the rollers 7 in the direction of the arrows (Fig. 7) the one 5 away from the other in lateral directions so that the surface of the door wings which fill the door frame is enlarged. The packings 14, 15 and 16, 17, slide the one on the other without pressure. The door wings are 10 guided, at this occasion, in the oval hinges 13. As the axes of the ovals are inclined at an acute angle α towards the direction of force indicated in Figs. 7 and 8 by an arrow not only the door wings are pressed against 15 the lateral packings 18 of the door frame but the packings 19 of the door wings are also strongly pressed against the packings 20 of the door frame. The door is thus securely latched at the ends where the hinges 20 are. The latching rod 1 presses then by means of the upper and lower latching wedges 3, 5 the right door wing through the guides 11 and the blocks 12 inward (Figs. 4, 9 and 5, 10). The vertical packings 14 25 are pressed upon the vertical packings 15 of the left door wing (Fig. 7) whereby the door is pressed together at the middle. At the same time the horizontal packings 17 of the door wing press upon the horizontal 30 packings 10 of the door frame (Figs. 9, 10) so that the door is securely and tightly packed along all its edges.

For opening the door the lateral latching is unlocked by pulling back the pushing 35 wedges 4. The packings push by their elasticity the door wings partly together towards the middle and the gravity of the door wings—these door wings being free to give way for a short distance under the 40 action of the gravity owing to the acute angled bolt guiding of the hinge 13,—effect the remaining unlocking work.

The latching rod 1 is held in the latching position and in the unlatching position, 45 in known manner by a nose on said rod 1, said nose engaging under a hinged bow if the latching rod is in the latching position and engages over said hinged bow if the latching rod is in the unlatching position.

The hinged bow is fixed on the right door 50 wing and it engages with an eye on the left door wing said eye being capable to be latched by a bolt and to be secured against unauthorized opening by a lead seal.

I claim:—

1. A device for latching doors heat-tightly or air-tightly, comprising in combination a latching rod shiftable in longitudinal direction, pushing wedges on said latching rod, pushing means fixed on each door wing in 60 the range of action of said pushing wedges, hinges of oval cross section on the door wings the oval of all hinges being inclined at the same acute angle towards the door plane, and a hand lever for lowering or 65 raising said latching rod said pushing wedges acting at the lowering of the latching rod upon said pushing means on the door wings so that the door wings are pressed towards the hinges the packing surface of the door being thus enlarged, the sideward push of each door wing being transformed by the oval guiding in the 70 hinges into a lateral push and into a transverse push.

2. A device for latching doors heat-tightly or air-tightly, comprising in combination a latching rod shiftable in longitudinal direction and having a slot near the upper end and a slot near the lower end, pushing 80 wedges on said latching rod, pushing means fixed on each door wing in the range of action of said pushing wedges, and a hand lever for lowering or raising said latching rod said pushing wedges acting at the lowering of the latching rod upon said pushing means on the door wings so that the door wings are pressed toward the hinges the packing surface of the door being thus enlarged, a latching block fixed on the upper 85 part of the door frame, a latching block fixed on the lower part of the door frame, and a guide rotatably mounted on each latching block and engaging with the corresponding slot of said latching rod so that 90 they take the rod along without friction.

In testimony whereof I affix my signature
ALFRED CARL FRIEDRICH RATHKE
